H. ROBERTS.
CLOTH GUIDING DEVICE.
APPLICATION FILED NOV. 7, 1916.

1,326,531.

Patented Dec. 30, 1919.

UNITED STATES PATENT OFFICE.

HERBERT ROBERTS, OF KEIGHLEY, ENGLAND.

CLOTH-GUIDING DEVICE.

1,326,531.

Specification of Letters Patent. Patented Dec. 30, 1919.

Application filed November 7, 1916. Serial No. 129,944.

To all whom it may concern:

Be it known that I, HERBERT ROBERTS, a subject of the King of Great Britain, and resident of Keighley, in the county of York, 5 England, have invented a certain new and useful Improvement in Cloth-Guiding Devices, of which the following description, having reference to the accompanying sheet of drawings, is a specification.

10 My invention relates to improvements in devices for guiding cloth through machinery or apparatus to the treatment of which it has to be subjected by being rapidly passed through same. My said invention is especially applicable for use in such types or classes of said machinery as require said cloth to be gathered together somewhat in the form of a rope with its ends or extremities stitched or otherwise connected together 15 so that the whole may be made to follow a spiral path by being arranged to take several times around certain of the operating rollers and other parts of the machines.

One of the types of said machines for 20 thus treating fabrics is well known as a "milling" or "fulling" machine, and it is in connection with this machine that I have hereinafter described my invention, since to those who have a knowledge of the finishing and treatment of fabrics, such description will clearly show or indicate to them how my said invention may be applied to other kinds or classes of apparatus.

When said milling or fulling machine is 25 in operation with the coils of cloth or fabric traveling in their respective paths, one coil is often caused to travel crosswise the other coils with the result that it becomes twisted thereby causing the fabric to curl 30 up into lumps or knots. When such is the case, the guiding or draft board in the machine, although acting to arrest the motion of said machine, is not in all cases quick enough so to do without the rapidly traveling cloth being damaged. To avoid the occurrence of these damages by providing 35 means which shall move so that one coil of fabric may not become crosswise the other coils and so that all twisting actions on the 40 part of said fabric are counteracted and to a great extent prevented, is the object of my present invention.

In the accompanying sheet of drawings:—

Figure 1 is a sectional side elevation of 45 sufficient of a cloth milling or fulling ma-

chine to illustrate the application thereto of my improved device.

Fig. 2 is a sectional elevation of my improved device drawn to an enlarged scale, so that its construction may be more readily 50 understood.

Fig. 3 is a plan of the parts shown by Fig. 2.

Fig. 4 is a sectional elevation of a modification of my improved parts as hereinafter 60 described.

Fig. 5 is a sectional plan of the parts shown by Fig. 4.

A indicates the framework or outer casing of the machine. 70

Similar letters and figures of reference indicate like parts throughout the several views.

On the fabric being introduced to the machine illustrated by Fig. 1, one end of same 75 is firstly passed through the spout *a* between the rollers *b* and *c* and through the trough or spout *d* over which the hinged cover *d*¹ takes, said cover *d*¹ being pivoted on the shaft of the upper roller *b* and weighted by 80 weights *d*² in manner well known. The fabric on leaving the spout *d* descends within the casing *A* and passes beneath the guiding roller or bar *f* and forward through one of several openings in the board known as 85 the "draft board" *g*. This draft board *g* is pivoted upon a bar *g*¹ which extends across the machine so that said board *g* may be at liberty to rise when acted upon by any 90 knots or irregularities in the fabric as same passes through the openings in said board *g* for the purpose of arresting the motion of the machine in manner well known. After the fabric is passed through one or other of the openings in the board *g* as above 95 stated it is conducted over the guiding roller *h* and again through the spout *a*, forward between the rollers *b* and *c*, through the trough *d* around the roller *f*, again 100 through another opening in the board *g* and again forward over the roller *h*, (the path followed by said fabric is indicated by the chain line *x*, and the direction in which it travels is indicated by the arrows *y*) the 105 number of times that it is thus carried or conducted in this direction or path is determined by the nature of the fabric and the requirements as to its treatment by the several parts of the machine as is well known to those who have a knowledge of this appa- 110

ratus. After the number of coils that are desired to pass through said machines in the manner described has been completed, then the end of the fabric which was first 5 led through the spout *a* will be brought to the rear end of the fabric where it will be stitched to said rear end in order that the coils of fabric thus arranged may be caused to travel by the rotary actions of the rollers 10 *b* and *c* in manner well known.

My new guiding devices as applied to said machine, consist of a circular board or plate *k* (see Figs. 2 and 3) which I mount in an appropriately formed opening *g*² made 15 through the board *g*. This board *g* has a flange *g*³ which will support the circular plate *k* when the machine is not in use, while the outer peripheral edge of the plate *k* is formed (and if the plate *k* is of wood, then 20 such edge is protected by an annular rim of suitable metal *k*¹) for contact with anti-friction balls *m* mounted above it, against which balls said plate *k* is pulled or forced by the moving fabric as its series of coils are 25 traveling in the direction hereinbefore described.

Above these balls *m* is mounted the annular part *n* which acts as a ball race so that on the machine being put into operation, 30 with the series of coils of fabric passing through the series of holes or openings *k*² made through the plate *k*, this latter is free to rotate and does rotate or oscillate as it is pulled in one direction or the other as the 35 fabric is deflected or drawn to one side or the other during its rapid motion through the machine as hereinbefore described. By the plate *k* being thus free to oscillate and move as the deflecting of the fabric may 40 cause it so to do, I have found that practically all twisting actions of said fabric are prevented and that the knotting or lumping of same is entirely avoided with the result that the fabrics being treated are not 45 damaged.

Although I have shown three holes or openings *k*² through the plate *k* it must be understood that the number of such holes is determined by the number of coils of fabric or the number of times that such 50 fabric has to be conducted through the plate *k*.

As the plate *k* is mounted upon the ordinary board *g* which still retains its hinged bearings said board *g* may yet move in the 55 ordinary manner to arrest the motion of the machine.

When my improved rotary guide plate *k* is used in other machines and in connection with other apparatus where only one hole is 60 required to be made through same, the construction illustrated in Figs. 4 and 5 may be applied, in which a rotatable plate *k*^a is employed shaped to provide a ball race 65 operating with a flange *n*^a, antifriction balls *m*^a being interposed between said plate and said flange.

Such being the nature and object of my invention what I claim is:—

1. In a fabric guiding device, a pivotally 70 supported draft board provided with an opening therein, a rotatable guide plate mounted opposite said opening, an annular flange attached to said board and surrounding said plate, and anti-friction members interposed between said flange and said plate, 75 whereby the plate is free to rotate during the passage therethrough of a twisting fabric.

2. In a fabric guiding device, a pivotally supported draft board provided with an 80 opening therein, surrounded by an annular shoulder, a rotatable plate resting upon said shoulder, and anti-friction means for retaining said plate in position, said plate being provided with a plurality of openings for 85 the passage of cloth, the plate being free to be rotated by the twisting of a fabric passing therethrough,

HERBERT ROBERTS.
